BOAT PLANING FIN

Niklas F. Zetterberg, 156 Muerdago Road,
Topanga, Calif. 90290

Filed May 11, 1972, Ser. No. 252,530

Term of patent 14 years

Int. Cl. D12—99

U.S. Cl. D12—70

FIG. 1 is a perspective view of my boat planing fin.

FIG. 2 is a side elevation of the same.

FIG. 3 is a rear view of the same.

FIG. 4 is a side elevation of the boat planing fin in another position.

The broken line disclosure of a portion of a transom is for illustrative purposes only.

I claim:

The ornamental design for a boat planing fin, as shown and described.
